UNITED STATES PATENT OFFICE.

JAMES I. PRIMM, OF TAMPA, FLORIDA.

ELEVATOR-GUIDE LUBRICATOR.

1,216,607.

Specification of Letters Patent. Patented Feb. 20, 1917.

Application filed October 3, 1916. Serial No. 123,486.

To all whom it may concern:

Be it known that I, JAMES I. PRIMM, a citizen of the United States of America, and a resident of Tampa, Hillsborough county, 5 and State of Florida, have invented certain new and useful Improvements in Elevator-Guide Lubricators, of which the following is a specification, reference being had to the accompanying drawings, forming a part 10 thereof.

My invention relates to improvements in elevator guide lubricators, and its object is to improve upon such devices as have been available heretofore and to provide a simple, inexpensive and efficient device which 15 is capable of applying the needed lubrication to the guides of elevator cars or counterweights, without loss and with but the minimum amount of attendance.

These and other objects of the invention 20 will be set forth in the following specification in which I will describe my invention, the novel features of which will be set forth in appended claims.

Referring to the drawings:

Figure 1 is a top plan view of an elevator guide lubricator which is made according to 25 and embodies my invention.

Fig. 2 is a sectional elevation of the left 30 hand portion of the apparatus shown in Fig. 1, it being understood that the right hand portion is similar in construction and arrangement to the parts shown.

Fig. 3 shows a half of one of the guide 35 brushes, this figure being a perspective view of a brush cut through its center on a plane represented by the cross-hatched surface.

Fig. 4 is an elevation of one of the upper 40 corners of an elevator car with one of my improved lubricators applied thereto, together with a portion of an elevator guide which is to be lubricated.

Like characters of reference designate 45 corresponding parts in all the figures.

10 designates the main body of the lubricator. This part is hollow and forms a reservoir for the oil 11 and also forms a support for the other parts of the device. It has substantially the form of a rectangular 50 box with a square recess 12 provided in one of its sides.

13 is a cover plate which fits over the body and closes the reservoir. This is provided with a filler opening covered by a 55 cap 14.

Left and right hand brush holders 15 and

16 each with a flange on its inner side, are affixed to the cover plate on opposite sides of the recess 12, and another brush holder 17 of similar construction but with a flange 60 on each of its sides, is affixed to the cover plate on the remaining side of the recess. All these parts are constructed preferably of metal such for example as aluminum alloy and fastened together by screws, bolts 65 or other suitable devices.

In each brush holder is an elevator guide brush 19 of cross section to form a slideable fit in the brush holders. These are pressed into engagement with the elevator guide 20 70 by compression springs 21. These brushes preferably are constructed of wood fiber. Their faces which are pressed against the guide are parallel with the surfaces of the guide and in intimate contact therewith. In 75 each of these faces is a transverse oil groove 22 which does not extend to the ends of the surface of the guides. The groove 22^A in the brush in brush holder 17 is shorter than those in the others because the end surface 80 of the elevator guide is narrower than the side surfaces thereof.

The brushes are further provided with holes 23 which extend from the oil grooves through the under side of the brushes. 85 Wicks 24 are fitted into these holes and held thereby. One end of each wick terminates at 25, before it reaches the oil groove so that each oil groove forms a closed oil chamber. The other ends dip into the oil 11. Slots 18 90 are provided in the cover plate 13 to allow for the passage of the wicks into the reservoir and to permit a longitudinal movement of the brushes.

The device is easily attached to the top 95 guide shoe of an elevator car or its counterweights, or to the car frame itself, by suitable brackets. When in place oil will be raised from the reservoir into the little inclosed oil chambers by capillary action, but can not escape while the car is at rest because the oil chamber except on its wick side, is entirely closed by solid surfaces. When the car moves however, a very thin film of oil will be left on the surfaces of the 100 guide, but the flat surfaces of the brushes prevent the application of an over-supply. These surfaces of the brushes also prevent the adhesion of any foreign matter to the 105 surfaces of the guides and further serve to give an even distribution of the lubricant. I have found that this device saves labor, oil 110

and trouble. There are no parts but the brushes subject to any wear and the life of these is long. Moreover, they may be easily replaced at but little expense.

5 The lubricator shown and described is of a form which I have found embodies my invention satisfactorily, but I do not intend to limit myself to any specific form or construction,—in fact I intend only such limitations as are imposed by the following 10 claims.

What I claim is:

15 1. An elevator guide lubricator comprising an oil reservoir, a brush having a flat surface adapted to run over a surface of the guide, said brush being constructed with a depression in said flat surface forming a closed oil chamber, an oil conduit connected with said chamber, and a wick fitted in said 20 conduit terminating near the oil chamber, the other end of said wick extending into the oil reservoir.

25 2. An elevator guide lubricator comprising an oil reservoir, a brush having a flat surface adapted to run over a surface of the guide, said brush being constructed with a transverse depression in said flat surface forming a closed oil chamber, an oil conduit connected with said chamber, a wick fitted in 30 said conduit terminating near the oil chamber, the other end of said wick extending into the oil reservoir, and a spring acting upon said brush to press said flat surface thereof against the guide surface.

35 3. An elevator guide lubricator comprising a hollow casing forming an oil reservoir, a brush guide thereon, a brush slidably supported in said guide, the outer end of said brush having a flat surface parallel with a 40 surface of the guide and being formed with a transverse recess forming a closed oil chamber, an oil conduit extending from said oil chamber through the brush to the lower surface thereof, a wick in said conduit terminating near the oil chamber with its other end extending into the oil reservoir, and a spring for pressing the flat end of the brush against the surface of the guide.

45 4. An elevator guide lubricator comprising a hollow casing forming an oil reservoir, a cover plate therefor, a brush guide thereon, a brush slidably supported in said guide, the outer end of said brush having a flat surface parallel with a surface of the guide and being formed with a transverse recess forming a closed oil chamber, an oil conduit extend-

ing from said oil chamber through the brush to the lower surface thereof, a wick in said conduit terminating near the oil chamber with its other end extending into the oil 60 chamber, a slot formed in said cover plate for allowing for the passage of said wick and for the movement of the brush in its guide, and a spring for pressing the flat end of the brush against the surface of the guide. 65

5. An elevator guide lubricator comprising a hollow casing forming an oil reservoir, said casing being constructed with a vertical recess to allow an elevator guide to pass through it, brush guides thereon on different 70 sides of said recess, a brush slidably supported in each guide, the outer end of said brushes having flat surfaces parallel with adjacent surfaces of the guides and being formed with recesses forming closed oil 75 chambers, an oil conduit extending from each of said oil chambers through its brush to the lower surface thereof, wicks in said conduits terminating near the oil chambers with their other ends extending into the oil 80 reservoir, and springs for pressing the flat ends of said brushes against the surfaces of the guides.

6. An elevator guide lubricator comprising a hollow casing forming an oil chamber, 85 a cover plate therefor, said casing and cover plate being constructed to form a vertical recess to allow an elevator guide to pass through it, a pair of brush guides on opposite sides of said cover plate, in alignment 90 with each other, an intermediate brush guide at the other side of the recess at right angles to the aforesaid pair of brush guides, brushes slidably supported in said guides, the outer ends of said brushes having flat surfaces 95 parallel with adjacent surfaces of the guide, each being formed with a transverse recess forming a closed oil chamber, an oil conduit extending from said oil chamber through the brush to the lower surface thereof, a wick in 100 said conduit terminating near the oil chamber with its other end extending into the oil reservoir, said cover plate being constructed with slots under the brush guides to allow for the passage of said wicks and for the 105 movement of the brushes in their guides, and a spring back of each brush arranged to press the flat end of each of the brushes against the adjacent surface of the guide.

In witness whereof, I have hereunto set 110 my hand this 28 day of September, 1916.

JAMES I. PRIMM.
